UNITED STATES PATENT OFFICE.

HENRY C. KARLSON, OF HASBROUCK HEIGHTS, NEW JERSEY.

TURBINE.

No. 846,855.

Specification of Letters Patent.

Patented March 12, 1907.

Application filed September 2, 1903. Serial No. 171,673.

To all whom it may concern:

Be it known that I, HENRY C. KARLSON, a citizen of the United States, and a resident of Hasbrouck Heights, in the county of Bergen and State of New Jersey, have invented a certain new and useful Turbine, of which the following is a specification.

This invention relates to turbine-wheels; and its objects comprise means by which the propelling fluid for a turbine-wheel is used expansively, means to easily reverse the rotation of the wheel, and other means to permit the wheel to maintain its axis of rotation in its center of gyration.

Referring to the drawings, Figure 1 represents vertical sections of a turbine-wheel as on the lines x x and x' x' of Fig. 3. Fig. 2 shows a partial vertical section on the line x^2 x^2 of Fig. 1. Fig. 3 represents a partial vertical section of the wheel with its shaft and appurtenances as on the line x^2 x^2 of Fig. 1. Fig. 4 is an end view, partly in axial section, of the flexible bearing with the shaft of the wheel. Fig. 5 represents a partial side view of a turbine-wheel with a plurality of concentric rings of buckets and their accompanying conduits.

The wheel is represented to consist of a central web A, extending from a hub B, the former having projecting from both of its sides vanes or buckets C C', that are covered at their outer edges by the rings C². The faces of the buckets are generated by lines parallel to the longitudinal axis of the wheel and are depressed in their middle portions, as shown. The buckets on the opposite sides of the central web A are reversed to each other, as shown at C and C'. A nozzle D has an opening that covers a specified number of buckets, and it is inclined to direct a fluid in a tangential direction to the periphery of the wheel.

A conduit F F' is located adjacent to the inner periphery of the buckets. Its inlet-opening at the end F is somewhat larger than the opening in the nozzle D opposite thereto, and its outlet-opening at F' is somewhat larger than the said inlet-opening F. The conduit is permanently secured in position by any suitable means. Between the openings F and F' the conduit is contracted, as shown at f, forming a neck smaller in cross-area than either opening. A second conduit G G' is permanently secured adjacent to the outer periphery of the buckets, with its inlet-opening G opposite the opening F' and some-

what larger than the latter, so as to extend over a greater length of buckets, and its outlet-opening G' is of greater length than its inlet-opening G, so as to extend over a greater number of buckets at its outlet-opening than at its inlet-opening, and the conduit is contracted, as shown at g, forming a neck smaller in cross-area than either opening. An exhaust-chamber can be located adjacent to the inner periphery of the buckets opposite the opening G', or the propelling fluid may escape directly into the casing in which the turbine revolves and from thence be led off. The nozzle D, conduits F F' G G', as represented in Fig. 1, are for the buckets C on one side of the central web A of the wheel, and similar appurtenances may be provided for the reversed buckets on the opposite side of said web.

The turbine is secured to a shaft I, an ordinary bearing being provided for the end i, and a resilient bearing K is located at the opposite end i'. The latter bearing consists of a plurality of chambers K', held in any suitable way and contain resilient washers K² or springs that force the bearing-pieces K³ against the periphery of the shaft I, the screws K⁴ adjusting the pressure on the said shaft.

To operate the invention, a fluid—steam, compressed air, and the like—issues from the nozzle D and enters the openings between the buckets opposite the said nozzle at the outer periphery of the wheel. The fluid impinges against and passes through the buckets, thereby rotating the turbine, and enters the inlet-opening F of the conduit F F'. The fluid then issues from the outlet-opening F', after passing through the contraction f to accelerate its velocity, and passing through the outlet F' again passes through the turbine, but engages a greater number of buckets than at the inlet-opening F, thereby again acting on the wheel to propel the same. Next the expanded fluid enters the inlet-opening G on the outside periphery of the wheel, passes the contraction g to accelerate its velocity, and issues from the outlet-opening G' to again enter the turbine through a still greater number of buckets, expands and further propels the turbine, and finally escapes. It is evident that the number of conduits could be increased. The shaft of the wheel bears against the bearing-pieces K³ of the resilient bearing and when turning will be enabled to locate its axis of rotation in

its center of gyration, causing the wheel to turn in perfect balance without straining the shaft.

My invention may be modified by locating 5 concentric rings of buckets at the periphery of the turbine-wheel, Fig. 5, connecting the outer ring of buckets C with the next adjacent ring of buckets C C by means of a conduit F² F², and then connecting the said ring C C 10 with the ring C² by means of the conduit F⁴ F⁵, and so on, building the turbine-wheel with numerous rings of buckets and their corresponding conduits.

Having described my invention, I claim—

- 15 1. In a turbine, the combination of a central web for the turbine, buckets with the walls at right angles to said web, extending from each side thereof, collars on the outer ends of the buckets parallel to the central 20 web, conduits adjacent to the inner periphery of the buckets, having outlet-openings of

larger area than their inlet-openings, conduits adjacent to the outer periphery of the turbine with outlet-openings greater than their inlet-openings, nozzles located to lead fluids to the buckets, and through the said conduits.

2. In a turbine, the combination of a plurality of concentric rings of buckets at the periphery thereof, means to impinge a propelling fluid against the buckets of one of said rings, conduits connecting the buckets of one ring with a greater number of buckets in the next adjacent ring.

Signed at the borough of Manhattan, in the 35 county of New York and State of New York, this 29th day of August, A. D. 1903.

HENRY C. KARLSON.
